UNITED STATES PATENT OFFICE.

FRANK J. GILROY, OF BUFFALO, NEW YORK.

RAILWAY-CAR.

1,118,277.

Specification of Letters Patent. Patented Nov. 24, 1914.

Application filed July 21, 1913. Serial No. 780,280.

To all whom it may concern:

Be it known that I, FRANK J. GILROY, a citizen of the United States, residing at Buffalo, in the county of Erie and State 5 of New York, have invented certain new and useful Improvements in Railway-Cars, of which the following is a specification, reference being had therein to the accompanying drawing.

10 The object of this invention is to provide cars adapted to serve, without change or addition, for a wide range of uses, and to serve in each case more satisfactorily than the special car usually employed for 15 the specific purpose. The same car answers perfectly for carrying ordinary merchandise, grain or other loose granular material, or automobile or other goods too large to pass into any ordinary car. The car is provided with two contiguous, oppositely sliding main doors placed edge to edge, and one of these doors has in its upper part a small door for loading granular material. Both 20 the main doors are adapted for continuous 25 marginal engagement, when closed, with flanges on the car itself. When the car is to be used like an ordinary box car, the loading door is closed and internally locked and one of the main doors is so secured as 30 to have all the strength of a part of the car wall, which it virtually becomes. When granular material is to form the load, the loading door is opened and then both main doors are closed and locked. When the 35 loading is completed, the small door is closed and automatically locked on the inside, so that it can not be again opened until the main doors are opened. When automobiles or similarly large pieces of freight 40 are to be carried, both main doors are opened for loading and then all the doors are closed and securely locked.

In the accompanying drawings, Figure 1 is a side elevation of the central portion of 45 a car provided with my devices. Fig. 2 is a section on the line 2—2, Fig. 1. Fig. 3 shows the outer face of a post at the meeting edges of the main doors. Fig. 4 shows the fastening for the upper end of the post, 50 looking from the interior of the car. Fig. 5 is a horizontal section through the post and the adjacent parts of the main doors. Fig. 6 is a sectional view showing the fastening devices at the lower end of the post. 55 Fig. 7 is a section on the line 7—7, Fig. 1. In these figures, A represents the side walls and B I-beam door posts of a car having sills D, upper framework E and floor F. Below the door opening and extending in each direction therefrom along the outside of the car is a fixed track G formed by the upturned marginal portion of a plate G' bolted to the car. Directly below the door opening this plate is widened and its upper marginal portion is bent outwardly 60 and then downwardly to form a hook or continuous flange G². At each door post an analogous vertical flange on the post extends from the lower to the upper side of the opening, and over the upper side of the 65 opening is an analogous downwardly projecting flange G⁴. Two doors H, H' cover the whole opening, the beveled vertical edge of one overhanging the contiguous oppositely beveled edge of the other. Both 70 are supported below by rollers I resting upon the track G, and both have below upturned marginal flanges J which engage the flange G², and at their outer lateral margins analogous inwardly turned or hooked flanges J' engaging the vertical flanges respectively, of the door posts when 75 both doors are closed. The upper margins of both doors slide beneath the flange G⁴, and the overhanging edge of one door prevents the independent outward springing of 80 the other. This overhanging marginal portion is itself held against outward movement by a vertical post shown as an I-beam K to which said margin is secured by rivets 85 or otherwise and which extends from the floor of the car to a head jamb or lintel above the door opening and slides bodily with the door to which it is secured. To the lower end of this post is rigidly fixed a 90 heavy metal member L grooved below in, or parallel to, the plane of the door to slide over a strong metal lug M projecting from a block M' sunk in the floor and bolted to 95 the car sill. A stop shoulder L' limits the 100 sliding in one direction, and a sliding bolt L² automatically locks it against return movement when that limit is reached.

At its upper end the post carries a block N which, like that at the lower end, is preferably of malleable iron or steel, adapted to slide as the door closes, behind a block O, securely fixed to the frame of the car, and to be locked against further sliding by a pin P. From the construction it is plain 110 that the post will resist any ordinary outward thrust upon itself or either door and

that when the door to which it is secured is closed, this door offers even greater resistance than other portions of the car wall. Moreover, the engagement of the door and 5 car flange at the upper, lower and rear or outer edge is such that granular material cannot pass, great pressure tending to make escape more difficult, if possible. This door being thus closed and the post locked in 10 place, the other door may be used as if the first door were a part of the car wall. Obviously when it is closed its forward margin lies beneath or within the overhanging edge of its companion and all its other edges 15 are in engagement at all points with flanges fixed to the car. This door is provided with small oppositely sliding loading doors Q having locking devices Q' not accessible from outside the car.

20 As has been stated, ordinarily the door secured to the central post is kept closed, but when necessary the post-locking bolts are withdrawn and door and post are moved aside together leaving a greatly enlarged 25 door opening.

It is to be observed that whatever the position of either door or the central post, all parts are securely held against moving from their normal plane into position for injuring 30 passing cars.

What I claim is:

1. The combination with a car having a continuous, door-overlapping flange extending along the upper side of a wide door 35 opening, continuous external flanges extending along all the remaining sides of that opening and turned from said opening, of two doors arranged to slide oppositely within the flange first mentioned and provided 40 with hooked flanges to engage at every point when the doors are closed, the lower and lateral flanges around said opening, the edge of one door being adapted to overlap the meeting edge of the other door and being 45 made substantially as inflexible as the body of the car wall.

2. The combination with a grain and automobile car having a continuous external, door-overlapping flange along the upper 50 side of a wide door opening, and continuous external flanges turned from said opening and extending along the remaining three sides thereof, of two oppositely sliding doors of thin metal, meeting centrally with respect

to said opening and one passing within an 55 overhanging margin of the other, a displaceable vertical beam extending from top to bottom of the opening, overlapped by both doors and secured to the door having the overhanging margin to keep it rigidly rectilinear; both said doors sliding within the flange first mentioned, provided with deflection-resisting reinforcement along their upper margins and along their lower and non-meeting margins with hooked flanges to 60 engage, when the doors are closed, the corresponding flanges around said opening.

3. The combination with a car having a continuous door-overlapping, external flange along the upper side of a wide door opening, 70 continuous external flanges turned from the opening and extending along the remaining sides thereof, and a track below said lower flange of two doors arranged to slide oppositely within the flange first mentioned and provided with hooked flanges to engage, at every point when the doors are closed, the lower and lateral flanges around the door opening, and with rollers to run upon said track, one door being provided 75 in its upper part with small internally locking grain doors, and the edge of one door being adapted to overlap the meeting edge of the other door and made substantially as inflexible as the body of the car wall.

4. The combination with a car having on all sides of its wide door opening continuous door-engaging flanges and provided at the upper and lower sides of said opening with heavy metal stops fixed to the frame 90 of the car centrally of the opening, of oppositely sliding doors of thin metal having all their margins stiffened by inwardly turned hooked flanges and all outer margins held when the doors are closed, at all points, 95 by the flanges, respectively, about said opening, and the margin of one door overhanging the meeting margin of the other door, and a T-beam fixed to said overhanging margin and adapted to slide into and out of 100 engagement with said stops as its door closes and opens.

In testimony whereof I affix my signature in presence of two witnesses.

FRANK J. GILROY.
